United States Patent Office

Des. 214,071
Patented May 6, 1969

214,071

PLATE

Ben Seibel, New York, N.Y., assignor to Fostoria Glass Company, Moundsville, W. Va.

Filed Feb. 5, 1968, Ser. No. 10,439

Term of patent 14 years

Int. Cl. D7—01

U.S. Cl. D36—2

FIG. 1

FIG. 2

FIGURE 1 is a partial side elevational and sectional view of a plate illustrating my new design, and taken substantially on the line 1—1 of FIGURE 2.

FIGURE 2 is a bottom plan view thereof.

I claim:

The ornamental design for a plate, as shown.
